SET OF EDUCATIONAL CHILDREN'S BLOCKS OR THE LIKE

William King Skinner, 102 NW. 15th St.,
Gainesville, Fla. 32601

Filed Mar. 14, 1969, Ser. No. 16,253

Term of patent 14 years

Int. Cl. D19—08

U.S. Cl. D25—1

FIG. 1

FIG. 2

FIG. 4

FIG. 5

FIG. 6

FIG. 7

FIG. 8

FIG. 9

FIG. 10

FIG. 11

FIG. 12

FIG. 13

FIG. 14

FIG. 15

FIG. 16

FIG. 1 is a plan view of one block of a set of educational children's blocks or the like, the block shown indicating a value 7;

FIG. 2 is a sectional view of the block shown in FIG. 1 taken along the lines 2—2;

FIG. 3 is a perspective of the block shown in FIGS. 1 and 2;

FIGS. 4 through 6 are plan views of blocks showing designs for a portion of a set of blocks, the designs thereon indicating values 1 through 3;

FIG. 7 is a plan view of a block of the set, the design thereon indicating the value 0;

FIGS. 8 and 9 are plan views of blocks of the set showing inverted designs of FIGS. 5 and 6; and

FIGS. 10 through 16 are plan views of blocks of the set, the designs thereon indicating the values 4 through 10.

All surfaces of the articles which are not shown are plain surfaces.

I claim:

The ornamental design for a set of educational children's blocks or the like, as shown and described.
